UNITED STATES PATENT OFFICE.

MICHAEL HERTZ, OF NEWARK, NEW JERSEY.

AUTOMATIC CIRCUIT BREAKER.

Application filed February 24, 1921. Serial No. 447,425.

To all whom it may concern:

Be it known that I, MICHAEL HERTZ, a citizen of the United States, residing at Newark, in the county of Essex, State of New Jersey, have invented certain new and useful Improvements in Automatic Circuit Breakers, of which the following is a description, reference being had to the accompanying drawing and to the figures of reference marked thereon.

This invention relates to electromagnetically controlled circuit breakers wherein a solenoid in series with the load is adapted to trip the breaker upon excessive load or upon short circuit and wherein it is impossible for the operator to maintain the circuit breaker closed as long as the excessive load or short circuit exists.

It is a particular object of my invention to form a neat, compact switch adaptable for mounting on the dashboard of an automobile, although it may be used in other relations.

It is another object of my invention to make a device of this character as of few parts and as cheap as possible.

Other objects will appear after reading the specification and claims in connection with the accompanying drawings, in which:

Figure 1 is a central longitudinal section through my circuit breaker with the circuit breaker in closed position.

Figure 2 is an end view thereof, with the end wall, adjacent the switch, removed.

Figure 3 is a section along the line 3—3 of Figure 1, the circuit breaker, however, being shown open.

Figure 4 is a view showing the position of parts just after the coil has been energized so as to withdraw the latching rod, the circuit breaker being tripped, and the latching rod being urged to its uppermost position.

Figure 5 is a view showing the normal relationship of parts, the circuit breaker being open.

Figure 6 is a plan view of the casing of the circuit breaker, the covering being removed, and

Figure 7 is a circuit diagram of the system including my circuit breaker.

Now referring to the drawings more in detail, 1 is a casing of moulded material such as bakelite, americanite or the like embedded in which is a pair of contacts 2 and

3, the contact 2 extending through the casing and being provided with a terminal nut 4. The other contact 3 is provided with a terminal 5 within the casing to which is secured as by a screw 6 a lead 7 of a solenoid 8, the other lead 10 of which is grounded into the metallic case 9 of the solenoid as by means of baring the wire at the point where it emerges from the casing and soldering it thereto as at 11. The lead 10 is secured to a terminal 12 in the bottom of the casing 1. The leads 7 and 10 are purposely made long so as to permit the solenoid to be removed from the casing 1 for inspection without disconnecting the lead wires from the terminals.

The solenoid is wound on a square hollow brass core 13, a suitable fibre insulator 14 being interposed between the windings and the metallic core. At one end the solenoid is provided with a soft iron core 15 provided with a stem 16 adapted to pass through a metallic insert 17 moulded into the casing and to be secured to the casing by means of a nut 18 and a suitable lock-washer. To securely hold the solenoid in place the metallic case 9 is spun over the coil and a washer 19 is interposed between the enlarged core portion 15 and the case 9, thereby causing the case 9 to be firmly wedged against the wall of the casing 1 when the nut 18 is tightened.

Slidable within the brass core of the solenoid is a soft iron square plunger 20 urged outwardly by a coil spring 21 made of non-magnetic material such as brass. Slidable in the outer end of the iron plunger is a circular latch rod 22 of some suitable insulating material such as fibre provided with a collar 23 and a shouldered portion 24, and a spring 25 is interposed between the collar 23 and the plunger 20 to urge the rod to the position shown in Figures 4 and 5. A stop pin 26 limits the upward movement of the latch rod while a dog 27 moulded into the casing 1 maintains the rod in latched position when the circuit breaker is in the position shown in Figure 1.

The latch rod co-operates with a square switch rod 28 journaled for reciprocal movement in the bottom of the casing, the casing being suitably provided with a square hole 29 which may be bushed if desired. The switch rod is urged upwardly to the position shown in Figures 3, 4 and 5 by means

of a spring 30 and the upward motion is limited by a stop pin 31 passing through the rod. The upper end of the switch rod carries a spring blade contact 32 adapted to 5 bridge the contacts 2 and 3, when the switch rod is in the depressed position shown in Figures 1 and 2.

Secured to the casing 1 is a cover plate 43 conveniently made of a punched metallic 10 piece provided with two cup shaped depressions 33 and 34. Seated in each of these depressions is a spring 35 and 36, respectively, which tends to maintain a resetting push button 37 and a circuit breaker tripping button 38 in extruded position, the outward limit of motion of these buttons being fixed by the stop pins 39 and 40 passing through the shanks of the buttons. The shank 41 of the push button 37 is of such a 15 length as to just clear the rod 22 in its elevated position, while the shank 42 of the push button 38 extends to a point slightly above the grounded case 9 of the solenoid. The cover plate is secured to the casing by 20 means of two screws 44 tapped into an insert 45 moulded in the casing and into a prolongation of the dog 27 already described. The dog may conveniently be made of an extruded bar having the cross section 25 shown in Figure 1 and cut off into pieces of convenient length. A lead 46 has one end clamped between the cover plate and a cut out portion 47 of the casing 1 to make electrical contact with the cover, and the other 30 end is connected with a terminal 48 in the bottom of the casing. The terminals 4 and 48 are adapted to be connected to opposite sides of a source of current such as a battery B while the terminal 12 is adapted to be 35 connected with the load L, the opposite terminal of the load being connected to that side of the source of current B which is in electrical connection with the terminal 48.

With the circuit breaker open, the parts 40 are as shown in Figure 5. When it is desired to close the circuit, the push button 37 is depressed and the motion thereof is transmitted through the latch rod 22 to the switch rod 28. When the latch rod 22 has 45 been sufficiently depressed, the spring 21 in the solenoid urges the rod 22 to the left in Figure 5, thereby causing the shouldered portion of the rod to engage underneath the dog 27. The push button 37 may now be 50 released. Upon short circuit or excessive load, the coil 8 is energized sufficiently to withdraw the latch rod 22 to permit the circuit breaker to be impelled upward by the spring 30 and at the same time, the rod 22 55 is also elevated as shown in Figure 4 by the spring 25. The spring 21 then acts to force the rod 22 into contact with the nose of the dog 27. Should the operator attempt to reset the circuit breaker with the short circuit 60 or excessive load still on the line, the sole-

noid would again be energized to trip the switch in spite of the fact that the button 37 is held depressed.

When it is desired to trip the switch to 70 break the circuit the push button 38 is depressed to make contact with the case 9 of the coil 8 which momentarily short circuits the load L to permit the coil to be energized sufficiently to pull in the plunger 20, to thereby trip the switch.

I have thus provided a neat, compact mechanism for automatically tripping the circuit under predetermined conditions, all of which is encompassed within a casing of relatively small dimensions, the circuit breaker being non-settable under conditions of overload or short circuit.

Having thus described my invention what I claim is:

1. In an automatic circuit breaker, a longitudinally movable switch, a longitudinally movable rod in alignment therewith but spaced therefrom, an electromagnet in series with the circuit breaker, a member controlled by said electromagnet and movable in a plane at right angles to the line of movement of the switch and rod interposed between the rod and the switch, said member being normally mechanically held in line to transmit a mechanical force from the rod to the switch but operable, under excessive load conditions, to break the continuity of the line.

2. In an automatic circuit breaker, a reciprocable switch member provided with resilient means to urge it to open position, a push rod in alignment therewith but spaced therefrom, a movable rod interposed between the switch member and the push rod and in alignment therewith, mechanical means to retain the movable rod in one of its positions to maintain the switch member in its closed position, resilient means to urge the movable rod to another of its positions when released from said retaining means, and electromagnetic means in series with the circuit breaker to move the movable rod out of engagement with the retaining means and out of alignment with the push rod and switch member when sufficiently energized.

3. In an automatic circuit breaker, a longitudinally reciprocable switch, a rod in alignment therewith but spaced therefrom, a member interposed between the rod and the switch, an electromagnet controlling the same, said member being normally mechanically held in line to transmit a mechanical force from the rod to the switch when the electromagnet is insufficiently energized but operable, under predetermined conditions, to break the continuity of the line, and a second rod substantially parallel to the first and under control of the operator for tripping the switch to open position.

4. In an automatic circuit breaker, a lon-

- gitudinally movable switch, a longitudinally movable rod in alignment therewith but spaced therefrom, an electromagnetically controlled member, movable in planes at 5 right angles to and parallel with the line of movement of the switch and rod interposed between the rod and the switch, said member being normally in line to transmit a mechanical force from the rod to the switch but 10 operable, under predetermined conditions, to break the continuity of the line, and a second longitudinally movable rod for the circuit breaker under control of the operator for closing a circuit through said electro- 15 magnet for tripping the switch to open position.
5. In an automatic circuit breaker, a reciprocable switch and a reciprocable rod movable in alignment therewith but spaced 20 therefrom, an electromagnetically controlled intermediate member normally mechanically retained in alignment with said switch and rod to transmit a mechanical force from the rod to the switch, said member being bodily 25 movable in a substantially rectangular path to accommodate itself to the position of the switch in either open circuit or closed circuit position and to break the line of transmission of force under predetermined condi- tions, and a second reciprocal rod for the circuit breaker under control of the operator for tripping the switch to open position. 30
6. In an automatic circuit breaker, a reciprocable switch, a longitudinally and laterally movable rod in alignment therewith, 35 latching mechanism for restraining the rod in switch closing position, electromagnetically operated means for moving the rod laterally to permit the switch to be opened, and resilient means for urging said rod longitudinally toward switch resetting position when released from said latching mechanism. 40
7. In an automatic circuit breaker, a reciprocable switch, a longitudinally and laterally movable rod in alignment therewith, 45 latching mechanism for restraining the rod in switch closing position, electromagnetically operated means in series with the circuit breaker for moving the rod laterally to 50 permit the switch to be opened, and resilient means for urging said rod longitudinally and laterally toward switch resetting position when released from said latching mechanism after the circuit breaker has been 55 opened.

In testimony whereof, I affix my signature.

MICHAEL HERTZ.
